UNITED STATES PATENT OFFICE.

EDWIN O. TOWNSEND, OF NEW YORK, N. Y.

DESIGN FOR A MONUMENT.

SPECIFICATION forming part of Design No. 29,861, dated December 20, 1898.

Application filed November 21, 1898. Serial No. 697,102. Term of patent 7 years.

To all whom it may concern:

Be it known that I, EDWIN O. TOWNSEND, a citizen of the United States, residing at the city of New York, borough of Manhattan, in the county and State of New York, have invented and produced a new and original Design for a Monument, of which the following is a specification, reference being had to the accompanying drawing, forming a part thereof, which represents a perspective view of a monument embodying the features of my design.

The leading feature of the design consists in a body that is in the semblance of an altar surmounted by the semblance of a cushion, the said cushion having battlement ornamentation. The base of the altar, which forms a subbase for the monument, is represented as partially smooth and partially in a rough or spalled condition, with battlement ornamenta-

tation at its rougher portions, said battlement ornamentation appearing embossed on corresponding smooth portions, and a plinth, the exposed surfaces of which are represented as having been spalled.

In the detail of the design the altar-like body is inclined from its base upwardly, and its upper margin is divided into arched panels, each of which panels is decorated with a leaf-like emblem, while a bead-like border is located below the arched panels, and the upright corners of the altar-like body are decorated with triangular intaglio panels.

I claim—

The design for a monument herein shown and described.

EDWIN O. TOWNSEND.
